UNITED STATES PATENT OFFICE

100,734

DESIGN FOR A DRUM

Hugo E. Lira, Milton, Mass.

Application April 16, 1936, Serial No. 62,162

Term of patent 14 years

To all whom it may concern:

Be it known that I, Hugo E. Lira, a citizen of the United States, residing at Milton, in the county of Norfolk, State of Massachusetts, have invented a new, original, and ornamental Design for a Drum, of which the following is a specification, reference being had to the accompanying drawing, forming part thereof.

Fig. 1 is a front perspective view of the drum, showing my new design;

Fig. 2 is a side elevational view; and
Fig. 3 is a top plan view thereof.

The dominant feature of the design consists of the rectangular outline of the drum.

I claim:

The ornamental design for a drum, as shown and described.

HUGO E. LIRA.
